(57) **CLAIM**

The ornamental design for a safety selector lever, as shown and described.

DESCRIPTION

FIG. 1 is a front-right angled view of a safety selector lever, showing the new design.

FIG. 2 is another front-right angled view thereof.

FIG. 3 is a front view thereof.

FIG. 4 is a top view thereof.

FIG. 5 is a bottom view thereof.

FIG. 6 is a left-side view thereof.

FIG. 7 is a right-side view thereof.

FIG. 8 is a front-right angled view of a safety selector lever, showing another embodiment of a new design.

FIG. 9 is another front-right angled view thereof.

FIG. 10 is a front view thereof.

FIG. 11 is a top view thereof.

FIG. 12 is a bottom view thereof.

FIG. 13 is a left-side view thereof; and,

FIG. 14 is a right-side view thereof.

The broken lines in the Figures depict unclaimed portions of the device or unclaimed environmental structure and are for illustrative purposes only. The broken lines form no part of the claimed design.
